TOY ROUNABOUT

Samuel I. Berger, Newark, N. J.

Application May 11, 1937, Serial No. 141,915

30 Claims. (Cl. 272—31)

The present invention relates to a toy round-about, and more particularly to a power driven toy device of the type in which a miniature airplane is mounted to fly around a stationary column or pylon.

Among the objects of the invention are to provide a toy of the general type referred to, which is amusing and intriguing in operation, which lends itself to comparatively inexpensive manufacture, and in which the flight of the airplane can be governed from a remote station by a control lever simulating in appearance and operation the conventional joy-stick of a full sized airplane, to cause the toy airplane to rise or descend, loop-the-loop, or undergo other stunt maneuvers in realistic manner.

As a feature of the present invention the control mechanism is such that an initial movement of the control lever in one direction establishes the drive between the motive power and the airplane so that flying impulses may be imparted to said airplane as desired and the speed of said airplane thereby regulated, a continued movement of said control lever in the same general direction causes the flying airplane to rise, and a movement of said lever transverse to said direction causes the airplane to undergo a looping action.

In a specific embodiment of the invention there is provided a shaft extending centrally through the pylon, a motor at the base of said pylon for driving said shaft, and an airplane supporting arm fulcrumed at the upper end of said pylon and rotatable with the shaft. The drive between the motor and the shaft is normally interrupted but is established by operation of the control lever. The raising of the airplane is effected by the application of a positive leverage force on the airplane carrying arm when the control lever is operated. For effecting the looping of the airplane the upper end of the pylon carries a power transmitting member preferably in the form of a disc held against rotation and movable by the control lever into or out of driving engagement with a freely rotatable power transmitting member preferably in the form of a friction wheel. This wheel is carried about the pylon by the airplane supporting arm and when engaged by said disc is caused to turn. This causes the arm to rotate about its own longitudinal axes and the airplane being mounted on an angular extension of said arm is caused to undergo a looping action.

In the accompanying drawings in which is

shown one or more of various possible embodiments of the several features of the invention—

Fig. 1 is a perspective view of the complete device of the present invention;

Fig. 2 is a section taken on line 2—2 of Fig. 1, with parts broken away, and showing the airplane in gliding flight after the drive between the motor and the main shaft has been interrupted;

Fig. 3 is a section taken on line 3—3 of Fig. 2;

Fig. 4 is a section taken on line 4—4 of Fig. 2 with parts broken away;

Fig. 5 is a section similar to Fig. 4 but showing the drive between the motor and the main shaft in engaged position;

Fig. 6 is a section similar to that of Figs. 2 and 3, but showing the setting for the elevated position of the airplane;

Figs. 7 and 8 are sections taken on lines 7—7 and 8—8 respectively of Fig. 3;

Fig. 9 is a fragmentary top plan view showing particularly the hub end of the device;

Fig. 10 is a section taken on line 10—10 of Fig. 3;

Fig. 11 is a section taken on line 11—11 of Fig. 2;

Fig. 12 is a bottom plan view of the remote control box and showing the control lever in released position;

Fig. 13 is a section of the remote control box taken on line 13—13 of Fig. 12;

Fig. 14 is a section taken on line 14—14 of Fig. 12;

Fig. 15 is a transverse section taken on line 15—15 of Fig. 14;

Fig. 16 is a section similar to that of Fig. 15, but showing the control lever in position to effect looping of the airplane; and

Fig. 17 is a section taken on line 17—17 of Fig. 14.

In the embodiment of the invention shown in the drawings there is provided a hollow column or pylon 10, surmounted on a base plate 11 which is relatively wide for stability. The pylon is preferably shaped from sheet metal to

form a rectangular motor housing 12 at its lower end, surmounted by a frusto-conical body 13, all of said parts being interlocked by the tongue and slot connections well known in the sheet metal toy art. Extending centrally through the pylon 10 is a main shaft 14, which is suitably supported and journaled in a manner to be

hereinafter described, and which is driven from an electric motor 15. This motor 15 is preferably of the synchronous A. C. type used in electric clocks and has the usual conductor cable 55

40
45
50
55

16 extending outwardly through the base plate 11 and terminating in a plug (not shown) adapted to be inserted in the ordinary house current outlet. If desired this plug may be provided 5 with the conventional switch.

Mounted on the upper end of the pylon 10 is a bracket 21, having a tubular section 22 which embraces the upper end of the shaft 14, and which is preferably secured thereto by a 10 cotter pin 20. The bracket 21 has a pair of spaced plates 23 extending transversely with respect to its tubular section 22 and supports for angular movement with respect thereto an arm 35 comprising a rod 19 preferably of wood, and a yoke 24 at one end of said rod having a pair of spaced plates 25 straddling the bracket plates 23 and fulcrumed thereon at 26. Integral with the forward ends of these yoke plates 25 is a cross brace 27, rotatably supporting a shaft 28, to 15 which is affixed a tube 29 by any suitable means, such as a cotter pin 30 passing through said tube, and a spacer sleeve 31 between said tube and said shaft. The tube 29 extends radially with respect to the axis of the shaft 14, and has fitted tightly therein one end of the rod 19, the other end having a depending extension 36 pivotally supporting a miniature toy dummy airplane 37 provided with a pin wheel propeller 34. By a dummy airplane is meant an airplane 20 having no tractive or control appurtenances carried thereby.

The pivotal connection between the arm extension 36 and the airplane 37 is preferably effected by means of a rod 38 extending centrally 25 through and affixed to the airplane fuselage, and having an upper exposed flat section 40 to which is secured by soldering or other suitable means a U-shaped member 41 for limiting the pivotal movement of the airplane, as will be made apparent. The rod section 40 extends through an elongated slot 42 in the base of this U-shaped member 41, and is pivotally connected at 43 above said base to the arm extension 36, the lower end of which is flat and extends through 40 said elongated slot. This lower end of the arm extension 36 is narrower than the length of the slot 42 so that the ends of said slot, when engaging the side of said extension respectively, will serve as limiting stops for the pivotal movement 45 of the airplane 37 with respect to said arm extension. The pivotal mounting of the airplane as described will cause it to travel on an even keel even as the inclination of the arm 35 is varied.

The weight of the airplane 37 and its supporting arm 35 is partially counterbalanced by two coil contractile springs 44, disposed between the pivotal connections 26 and the shaft 14, and anchored at one end 45 to the yoke plates 25 and at their other ends 46 to the bracket plates 23.

The motor 15 is provided with a shaft 50, journaled in a pair of spaced frame plates 51 and 52 in the housing 12, and drives the shaft 14 through a gear train which includes a pinion 53, affixed to said motor shaft 50 on the outer side of the frame plate 52, and meshing with a gear 53a mounted on a stub shaft 54, which is journaled on said frame plate 52, and which carries on its inner end a pinion 55. This pinion 55 meshes with a gear 56, affixed to a shaft 57 which extends 60 through the frame plate 52 and which is journaled near one end in the wall 58 of a gear housing 60 secured to the outer side of said frame plate 52. Affixed to this shaft 57 on the inner side of the frame plate 52 is a pinion 61, which 65 is normally urged out of mesh with a crown gear 75

62 affixed to the lower end of the shaft 14, but which may be moved into mesh with said crown gear by remote control as will be hereinafter set forth, to establish the drive to said shaft.

The crown gear 62 rests on a cross brace 63 5 between the frame plates 51 and 52, so that the shaft 14 is supported against downward endwise movement, and said shaft is held against upward endwise movement by a pair of spaced flanges 64, which extend upwardly from a plate 65 integrally 10 interconnecting the top of said frame plates and which are provided with inturned lips at their upper ends forming abutments for an enlarged section 66 of said shaft.

In order to urge the pinion 61 out of mesh with 15 the crown gear 62, there is provided a plate 70 on the outer side of the frame plate 52, pivotally mounted on the shaft 54, and carrying the shaft 57 which passes through an inclined elongated slot 71 in the frame plate 52. This plate 70 is 20 urged in a clockwise direction about the shaft 54 (Fig. 4) by a leaf spring 73, anchored at one end to a stud 74 on said plate, fulcrumed intermediate its ends over a pin 75 secured to the frame plate 52, and bearing at its other end 25 against the lower edge of one of the side walls 76 of the gear housing 60.

The clockwise movement of the plate 70 is limited by the engagement of the shaft 57 with the upper end of the slot 71, and in this limiting 30 position of said plate the shaft 57 will be slightly askew with the pinion 61 out of mesh with the crown gear 62, and the drive to the shaft 14 interrupted, as shown in Figs. 2 and 4.

In order to establish the drive between the motor 15 and the shaft 14 there is provided a cam 78 affixed to a shaft 80 journaled in the frame plates 51 and 52 and adapted to ride over the stud 74. This cam 78 is provided with a cut-out or low part 81, and is normally urged in counter-clockwise direction by a spring 96, as will be more fully described hereinafter, with said low part in contact with the stud 74, as shown in Fig. 4. The cam 78 may be moved in a clockwise direction by remote control means to be described, so that the 45 high part of the cam engaging the stud 74, moves the plate 70 in a counterclockwise direction about the shaft 54 against the action of the leaf spring 73, until the shaft 57 engages the lower end of the slot 71 as shown in Fig. 5. In this limiting 50 position of the plate 70, the shaft 57 will be straightened into horizontal position, the pinion 61 will move into mesh with the crown gear 62, and the drive to the shaft 14 will be established.

The means for establishing the drive to the 55 shaft 14 includes a remote control box 85, preferably round, and having a turret 86 provided with an elongated slot 87 through which extends a control lever 88. This lever 88 is pivoted on a cross pin 90 supported on opposite walls of 60 the turret 86 and has connected to its lower end one end of a flexible wire cable 91 passing through a tubular sheathing 92, the other end of said cable being connected to a lever arm 93 affixed to the shaft 80. This cable 91 is preferably provided with a turn buckle 95 by which the relative position of the various control elements may be adjusted.

The lever arm 93 is urged in a counterclockwise direction (Fig. 3) and the control lever 88 is normally maintained in the extreme angular position shown in Fig. 13 by a coil spring 96, one end of which is connected to the outer end of said lever arm 93, the other end being anchored to the base plate 11.

When it is desired to set the device into operation, the motor 15 is plugged into the house circuit so that it will rotate, and the pinion 61 is moved into driving engagement with the crown gear 62. The control lever 88 for that purpose, is moved a small angular distance in a clockwise direction about the pivot pin 90 from the position shown in Fig. 13. This operation causes the clockwise rotation of the lever arm 93 (Fig. 3) 10 against the action of the spring 96, and causes the corresponding clockwise rotation of the shaft 80 so that the cam 78 is rotated from the position shown in Fig. 4 to that shown in Fig. 5. This movement of the cam 78 causes the corresponding rotation of the plate 70 so that the pinion 61 meshes with the crown gear 62 and the shaft 14 is rotated. This rotation of the shaft 14 causes the circular movement of the airplane 37 about the pylon 10.

20 The continued movement of the control lever 88 about its pivotal support 90 after the establishment of the drive to the shaft 14 as set forth, causes the arm 35 to be raised about its pivotal support 26, so that the elevation of the airplane 37 during flight is correspondingly varied. For that purpose the shaft 14 is hollow and has extending therein a flexible wire cable 100, the upper end of which is anchored to a bar 101 pivotally supported on the yoke plates 25, the lower end being connected to a plunger 102 extending in the lower section of said shaft, and preferably formed from a flat metal bar reversely bent to form a tubular foot 103 of triangular cross section. This plunger 102 is pivotally connected to 30 a lever piece in the form of yoke 104 preferably by means of a pin 105 loosely passing through the plunger foot 103 and through a cross piece 106 extending between side plates 107 of said yoke. These yoke plates 107 are loosely mounted on the shaft 80, and are integrally interconnected by a cross plate 108. The lever arm 93 extends between these yoke plates 107, and is provided with a flange 110 adjacent to the cross plate 108, so that after the arm 93 has been rotated a slight angular distance in a clockwise direction (Fig. 3) 40 sufficiently to effect the establishment of the drive to the shaft 14 as set forth, this flange engages the plate 108 and causes the rotation of the yoke 104 about the axis of the shaft 80. This clockwise rotation of the yoke 104 pulls the cable 100 downwardly so that the yoke 24 is angularly raised about its pivotal support 26 and the elevation of the moving airplane 37 correspondingly raised, as shown in Fig. 6. The arm 35 thus forms a lever of the first class with the fulcrum at 26, and the point of application of the turning power at the connecting point between the cable 100 and the yoke bar 101.

When the manual operating pressure on the control lever 88 is released, said lever will return to its normal position shown in Fig. 13 under the action of the coil spring 96, the corresponding return movement of the lever arm 93 under this spring action being limited by an offset portion 55 65 112 (Fig. 3) on one of the yoke plates 107 serving as a catch for said lever. In this setting the inertia of the airplane will cause it to glide about the pylon at a gradually decreasing speed and to gradually go down.

70 In order to cause the airplane 37 to undergo a looping action, there is provided at the upper end of the pylon 10, a clutch element in the form of a disk 115, which is secured to a bushing 116 slidably embracing the bracket tube section 22, and which is guided for vertical movement by

means of a pair of guide rods 117 permanently secured to said bushing at their upper ends, and passing through a cross frame plate 118 of the pylon, and through a plate 120 forming the top of the motor housing 12. This disc 115 is fixed against rotation, and is urged in its lowermost position shown in full lines in Fig. 2 by coil springs 121 encircling the guide rods 117 respectively, and abutting at their upper ends the frame plate 118 and at their lower ends a disc 123 secured to said guide rods for axial movement therewith, and forming a bearing for the shaft 14. This lowermost position of the disc 115 is limited by the seating of the bushing 116 upon a centrally depressed section 124 of a cap piece 125 secured to the upper end of the pylon 10. Affixed to the shaft 28 is a gear 130 meshing with a gear 131 secured to a shaft 132 which is journaled in the cross piece 27 and which carries at one end thereof a clutch element in the form of a friction wheel 133. This friction wheel 133 is out of engagement with the disc 115 in any angular operating position of the arm 35 when the disc 115 is in the position shown in Fig. 2.

20 In order to move the disc 115 upwardly into the wheel engaging position shown in dotted lines in Fig. 2, there is provided a bell crank lever 140 (Figs. 2, 3, 6 and 10) which is pivotally mounted on a shaft 141 extending between the frame plates 51 and 52, and which has a downwardly 30 extending arm 142 and a substantially horizontally extending arm 143, said latter arm being bifurcated at its outer end to straddle the shaft 14 below the lower ends of the guide rods 117. This bell crank 140 is urged in a counter-clockwise direction (Fig. 3) by a coil spring 144, connected at one end to the lower end of the bell crank arm 142, and connected at its other end to the base plate 11. When this bell crank 140 is moved in a clockwise direction by the operation of the control lever, as will be hereinafter described, the prongs 145 of the bifurcated end of the arm 143 will engage the guide rods 117 and move them upwardly to cause the corresponding upward movement of the disc 115 into wheel driving engagement.

35 The clockwise rotation of the bell crank lever 140 is effected by the operation of the control lever 88 in a transverse direction from that heretofore described, and for that purpose the turret 50 55 86 includes an inverted box-like member 150 having a rectangular cross section, and pivotally connected at 151 to a pair of flanges 152 extending upwardly from the top of the control box 25. Journaled in the walls of the control box 25 55 is a rock shaft 153 to which is secured a lever piece 154 disposed directly below the turret member 150, said piece comprising a yoke having a cross plate 157 and a pair of flanges 155 and 156 through which extends the shaft 153. The 60 flange 154 is shown triangular in shape (Fig. 14) with its apex connected to one end of a flexible wire cable 158 passing through a sheathing 159, the other end being connected to the lower end of the bell crank arm 142.

65 The end wall 160 of the extension member 150 is spaced from the rock shaft 153 as shown in Fig. 12, and the lower edge of the side wall 161 of said member is directly above the cross plate 157 of the lever piece 154, so that when the lever 70 75 88 is moved transversely to the position shown in Fig. 16, the member 150 will be tilted about its pivotal supports 151, and said side wall engaging said cross plate will cause the lever piece 154 to be tilted in a clockwise direction from 75

the position shown in full lines in Fig. 14, to the dotted position shown in said latter figure. This angular movement of the lever piece 154 will cause the movement of the bell crank lever 140 as already described, to cause rotation of the airplane supporting arm 35 about its longitudinal axis.

When the manual transverse operating pressure on the control lever 88 is released, said lever 10 and the extension member 150 will return to the position shown in Fig. 15 under the action of the spring 144. In order to limit this return movement of the lever 88 and the member 150, the end wall 163 of said latter member extends 15 below the top wall 164 of the box 85, and has a transverse extension 165 engaging the bottom of said top wall in limiting position as shown in Fig. 17.

Although the operation of the device is apparent, it may be briefly summarized as follows:

As soon as the conductor cable 16 is plugged into the socket of the ordinary house circuit and the motor circuit closed, the motor 15 will start rotating, but since the drive to the shaft 14 is interrupted, the arm 35 will remain stationary and the airplane will be in its lowermost position close to the ground. Upon initial movement of the control lever 88 about its pivotal support 90, the pinion 61 will move into mesh 25 with the crown gear 62, so that the shaft 14 will be rotated. This causes rotation of the arm 35 and corresponding circular movement of the airplane 37 about the pylon 10, this airplane movement causing the propeller 34 to rotate in 30 the manner of a pin wheel. By selectively operating the lever 88 in and out of driving position with respect to the shaft 14 the speed of the airplane 37 may be regulated.

If it is desired to raise the elevation of the 40 airplane 37 after the drive to the shaft 14 has been established, the control lever 88 is moved beyond its initial shaft driving position to cause the plunger 102 and its attached cable 100 to be pulled downwardly, so that the arm 35 will be 45 raised about its pivotal supports 26 as shown in Fig. 6.

If it is desired to have the airplane 37 undergo looping action during flight, the lever 88 is moved transversely into the position shown in 50 Fig. 16 to cause the disc 115 to move upwardly into engagement with the friction wheel 133 so that as the arm 35 swings about the pylon, said wheel rotates by its frictional engagement with disc 115. Through the intermeshing gears 130 55 and 131, arm 35 is caused to rotate about its own axis in a direction which will cause the airplane 37 to be tilted upwardly and to effect a forward back loop, this looping action of the airplane being repeated as long as the control lever 88 is 60 maintained in the position shown in Fig. 16. This looping may be effected while the airplane is being positively rotated about the pylon 10 or while the drive to the shaft 14 is interrupted and the airplane is gliding, and may be effected 65 in any elevation of said airplane.

It is seen, therefore, that by the selective operation of the lever 88 in any of its control positions and in a manner similar to that of a joystick, the airplane may be made to perform unusual realistic operations simulating corresponding maneuvers of a full sized airplane.

It will thus be seen that there is herein described a device in which the several features of this invention are embodied, and which device 75 in its action attains the various objects of the

invention, and is well suited to meet the requirements of practical use.

As many changes could be made in the above construction, and many apparently widely different embodiments of this invention could be made 5 without departing from the scope thereof, it is intended that all matter contained in the above description or shown in the accompanying drawings shall be interpreted as illustrative and not in a limiting sense.

Having thus described my invention, what I claim as new and desire to secure by Letters Patent is:

1. A toy of the class described including, a 15 column, a rotatable bracket mounted at the upper end of said column, and having a pair of spaced plates, a yoke having a pair of spaced plates contiguous to the respective bracket plates and pivotally mounted thereon, a rod connected to said yoke, a toy member at the outer end of said rod, means for swinging said yoke about its pivotal support and means for effecting loop-the-loop rotation of said toy member.

2. A toy of the class described including a 25 column, a rotatable bracket mounted near the upper end of said column and having a pair of spaced plates, a yoke having a pair of spaced plates straddling said bracket plates and hinged thereon, a cross-bar connected to and extending between said yoke plates, and spaced from the hinge support of said latter plates, a rod connected to said yoke, a toy member supported at the outer end of said rod, a cable connected to said cross-bar substantially midway thereof, and control means for pulling said cable to effect the angular movement of said yoke about its pivotal support.

3. A toy device of the class described, including a column, a shaft extending centrally of said column, a bracket having a tubular section 40 embracing the upper end of said shaft and connected thereto for rotation therewith, an arm pivotally supported on said bracket, a toy member at the outer end of said arm, a motor in the base of said column, a drive connection between 45 said motor and said shaft, a cable extending through said shaft and connected at its upper end to said arm at a section spaced from its pivotal support, means for pulling said cable downwardly to raise said arm about said pivotal support and including a control member manually operable from a predetermined station, irrespective of the rotation of said shaft and means operable from said control member for rotating said toy member about an axis other than the 55 axis of said shaft and the pivotal axis of said arm.

4. A toy device of the class described, including a column, an arm rotatably fulcrumed near the upper end of said column, a toy member at 60 the outer end of said arm, a lever piece near the base of said column, and having a fixed pivotal support with respect to said column, a tie member between said lever piece and said arm extending substantially vertically through said column, a control lever spaced from said column, and a cable between said control lever and said lever piece for rotating said lever piece upon movement of said control lever to effect the angular movement of said arm about its fulcrum 65 support.

5. A toy of the class described, including a 70 pylon, a shaft extending vertically through said pylon, an arm mounted at the upper end of said pylon, connecting means between said shaft and 75

5 said arm for bodily rotating said arm about the axis of said shaft and with said shaft, upon rotation of said shaft, a toy member at the outer end of said arm, a source of motive power spaced from said toy member, and fixed with respect to said pylon, a drive connection between said source and said shaft, having a transmission member movable into or out of operative power transmissive position with respect to said source 10 of power, means for maintaining said transmission member out of operative transmissive position to interrupt said drive connection, and control means spaced from said pylon for moving said transmission member into operative transmissive position to establish said drive connection, and thereby effect rotation of said shaft.

6. A toy of the class described, including a pylon, a shaft extending vertically through said pylon, an arm supported near the upper end of said pylon, connecting means between said shaft and said arm for bodily rotating said arm about the axis of said shaft and with said shaft, upon rotation of said shaft, a toy member supported from the outer end of said arm, a fixed motor 20 at the base of said pylon, a drive connection between said motor and said shaft, including a pair of intermeshing gears, spring means for urging said gears out of intermeshing engagement, whereby said drive connection is interrupted, and control means for moving said gears 25 relatively into intermeshing relationship against said spring means for establishing said drive connection and rotating said shaft.

7. A toy of the class described, including a pylon, a shaft extending vertically through said pylon, an arm supported near the upper end of said pylon, connecting means between said shaft and said arm for bodily rotating said arm about the axis of said shaft and with said shaft, upon rotation of said shaft, a toy member supported on the outer end of said arm, a fixed motor on the base of said pylon, a gear train between said motor and said shaft and including a crown gear, and a pinion adapted to mesh with said crown gear, means for urging said pinion out of mesh with said crown gear, and means for moving said pinion into mesh with said crown gear to establish a drive connection between said motor and said shaft.

8. A toy device of the class described, including a pylon, a shaft extending centrally through said pylon, an arm supported near the upper end of said pylon, connecting means between said shaft and said arm for bodily rotating said arm about the axis of said shaft and with said shaft, upon rotation of said shaft, a toy member at the outer end of said arm, a motor in the base of said pylon, a drive connection between said motor and said shaft, including a pair of gears, spring means normally urging said gears out of mesh whereby said drive connection is interrupted, and means including a cam for moving said gears relatively into intermeshing relationship against said spring means whereby said drive connection is established.

9. A toy device of the class described, including a column, an arm rotatably fulcrumed near the upper end of said column, a toy member supported at the outer end of said arm, a motor, a drive connection between said motor and said arm normally in interrupted state, a lever arm, a lever piece, said lever piece and said lever arm being so arranged that upon the angular movement of said lever arm a predetermined angular distance it will engage said lever piece and cause

the angular movement of said latter piece, a control member for rotating said lever arm about its pivotal support, means actuated by the angular movement of said lever arm for establishing said drive connection, and means actuated by the rotation of said lever piece for raising said airplane supporting arm angularly about its fulcrum support.

10. A toy of the class described, including a captive toy airplane, a motor, a train of gears between said motor and said airplane including a pair of cooperating gears, a shaft for one of said gears, a pivoted plate supporting said shaft, spring means urging said plate in position whereby said latter gear is out of mesh with its cooperating gear, a cam cooperating with said plate, and control means for rotating said cam to effect the angular movement of said plate about its pivotal support to bring the gear supported thereon into mesh with its cooperating gear whereby the drive to said airplane is established.

11. A toy of the class described, including a captive airplane, a motor, a train of gears between said motor and said airplane, including a crown gear and a pinion adapted to mesh with said crown gear, a shaft for said pinion, a pivoted plate supporting said shaft, spring means urging said plate in a direction about its pivotal support to maintain said pinion out of mesh with said crown gear, a cam cooperating with said plate for rotating said plate against the action of said spring means and control means for rotating said cam against the action of said spring to effect rotation of said plate in position to bring said pinion into mesh with said crown gear whereby the drive to said airplane is established.

12. A toy device of the class described, including a pylon, an arm at the upper end of said pylon, a toy airplane at the outer end of said arm, means for rotating said arm about said pylon, a drive connection for rotating said arm about its own longitudinal axis and including a clutch element held against rotation, and a second clutch element carried by said arm and movable therewith about said pylon and means for moving said elements relatively into or out of driving inter-engagement.

13. A toy device of the class described, including a pylon, an arm supported at the upper end of said pylon, a toy airplane connected to the outer end of said arm, means for rotating said arm about said pylon, a freely rotatable clutch element movable with said arm about said pylon, a drive connection between said element and said arm to effect the rotation of said arm about its longitudinal axis upon the rotation of said element, an axially slid able clutch element on the upper end of said pylon held against rotation, and means for axially moving said latter element into or out of driving engagement with said first mentioned clutch element.

14. A toy of the class described, including a pylon, an arm at the upper end of said pylon, a toy airplane at the outer end of said arm, means for rotating said arm about said pylon, a drive connection for rotating said arm about its longitudinal axis and including a freely rotatable friction wheel carried by said arm, and movable therewith about said pylon, and a disc at the upper end of said pylon held against rotation, a rigid rod connected to said disc and extending downwardly in said pylon, a spring means urging said disc to a limited lowermost position, a lever below the lower end of said rod and adapted to engage said rod upon angular movement of said

- lever and control means for rotating said lever to effect upward movement of said rod, and corresponding movement of said disc into driving engagement with said friction wheel.
5. 15. A toy device of the class described, including a pylon, a shaft extending centrally through said pylon, an arm at the upper end of said pylon and rotatable with said shaft, a toy airplane at the outer end of said arm, a drive connection for rotating said arm about its own longitudinal axis and including a clutch element held against rotation and slidably embracing the upper end of said shaft, a pair of guide rods connected to said clutch element and extending 10 downwardly on opposite sides of said shaft, spring means urging said clutch element to a lowermost inoperative position, lever means near the base of said pylon adapted to engage the lower ends of said guide rods and remote control means for operating said lever means to effect upward movement of said clutch element 15 into driving position with respect to said arm.
16. A toy of the class described, including a pylon, a shaft extending centrally through said 20 pylon, an arm at the upper end of said pylon rotatable with said shaft, a toy airplane at the outer end of said arm, means for driving said shaft, a drive connection for rotating said arm about its own longitudinal axis and including a 25 disc held against rotation, and a freely rotatable friction wheel movable with said arm about said pylon, a pair of guide rods secured to said disc and extending on opposite sides of said shaft, a crank lever near the base of said pylon, one arm 30 of which is bifurcated and straddles said shaft below said guide rods, and means for rotating said crank lever whereby said crank arm engages said guide rods and moves said disc into driving 35 engagement with said frictional wheel.
40. 17. A toy of the class described, including a pylon, a captive toy airplane supported on said pylon, a motor spaced from said airplane, a drive connection between said motor and said airplane, a control lever spaced from said pylon and said airplane, and means responsive to the 45 movement of said control lever in one of three different control positions to effect engagement of said drive connection, positive lifting of said airplane to vary its elevation, or looping of said airplane respectively.
50. 18. A toy device of the class described including a pylon, a shaft extending centrally through said pylon, an arm pivotally mounted on the upper end of said pylon for rotation with said shaft, a dummy toy airplane at the outer end of said arm, a control lever spaced from said pylon, means responsive to the movement of said control lever in one direction for driving said shaft, means responsive to the continued movement of 55 said lever to angularly move said arm about its pivotal support to effect variation in the elevation of the airplane, and means responsive to the movement of said lever in a transverse direction to effect the rotation of said arm substantially about its longitudinal axis whereby said airplane is caused to effect looping action.
60. 19. A toy device of the class described, including a pylon, a captive dummy toy airplane supported on said pylon, a motor spaced from said airplane for rotating said airplane about said pylon, a control lever spaced from said pylon, means responsive to the movement of said control lever in one direction for effecting one control setting for said airplane, means responsive to the continued movement of said lever to effect 65
- a second control setting for said airplane, and means responsive to the movement of said lever in a transverse direction to effect a third control setting for said airplane.
5. 20. A toy device of the class described, including a captive toy dummy airplane, a fixed motor, a normally interrupted drive connection between said motor and said airplane, a control lever spaced from said airplane, means responsive to the angular movement of said control lever about its pivotal support for establishing said drive connection whereby said airplane is made to move along a circular path, and means responsive to the continued angular movement of said control lever for varying the elevation of said airplane while maintaining said airplane against looping rotation.
21. A toy of the class described, including a column, an arm rotatably fulcrumed near the upper end of said column, a toy airplane at the outer end of said arm, a fixed motor, a normally interrupted drive connection between said motor and said arm for rotating said arm about said column, a control lever spaced from said column and said airplane, means responsive to the movement of said control lever about its fulcrum support for establishing said drive connection, and means responsive to the continued movement of said lever about said fulcrumed support for applying a positive leverage force on said arm to raise said arm about its fulcrumed support while maintaining said airplane against looping rotation.
25. 22. A toy of the class described, including a captive dummy toy airplane, a control lever spaced from said airplane, means responsive to the movement of said lever in one direction for raising said airplane, and means responsive to the movement of said lever in a transverse direction for subjecting the airplane to looping action.
30. 23. A toy of the class described, including a captive dummy toy airplane, a control lever spaced from said airplane, means responsive to the movement of said lever in one direction for causing the circular movement of said airplane about a vertical axis and means responsive to the movement of said airplane in a transverse direction for subjecting the airplane to looping action.
35. 24. A toy of the class described, including a captive dummy toy airplane, and control means for said airplane spaced from said airplane and including a control box, a turret on said control box, pivotally supported for rocking movement with respect to said control box, and a control lever pivotally supported on said turret, the axes of the pivotal supports for said lever and said turret being transverse with respect to each other.
40. 25. A toy of the class described, including a captive dummy toy airplane, and control means for said airplane spaced from said airplane and including a control box, a turret on said control box pivotally supported for rocking movement with respect to said control box, a control lever 45 pivotally supported on said turret, the axes of the pivotal supports for said lever and said turret being transverse with respect to each other, and a lever piece in said control box engaged by said turret in its rocked angular position and rotated by said turret.
45. 26. A toy device of the class described, including a column, an arm fulcrumed near the upper end of said column, a toy member at the outer end of said arm, means for rotating said arm 50

about said column, control means for applying a positive leverage force on said arm to raise said arm about its fulcrum support, and means for rotating said arm substantially about its own longitudinal axis.

27. A toy device of the class described, including a column, an arm fulcrumed near the upper end of said column, a toy member at the outer end of said arm, means for rotating said arm about said column, a control member remote from said column and said arm, and means responsive to the movement of said control member into two operating positions, for applying a positive leverage force to said arm to raise said arm about its fulcrum support, and for rotating said arm substantially about its longitudinal axis respectively.

28. A toy device of the class described, including a hollow vertical shaft, means for rotating said shaft, an arm near the upper end of said shaft extending transversely outwardly therefrom, and rotatable with said shaft, a toy member at the outer end of said arm, a lever piece near the base of said shaft, having a fixed pivotal support with respect to the axis of said shaft, and having a section spaced from said pivotal support, and disposed substantially in longitudinal alignment with said shaft, a stress transmitting member between said lever section and said arm extending substantially vertically through said shaft, and connected at its lower end to said lever section, and a control member for rotating said lever piece about its pivotal support for effecting angular movement of said arm about its fulcrum support.

29. A toy device of the class described, including a column, an arm fulcrumed near the upper

end of said column, a toy member at the outer end of said arm, means for rotating said arm about said column, and control means operable independently of said toy member for applying a positive leverage force on said arm to raise said arm about its fulcrum support, and including a force transmitting member having a point of power application spaced from said fulcrum support, a control member remote from said arm and said column and manually operable from a stationary position with respect to the rotatable arm to stress said force transmitting member, and flexible transmission cable means between said control member and said column, said control member being non-rigidly supported with respect to said column to permit said control member to be moved and placed into selective operating positions with respect to the column for control operations.

30. A toy device of the class described, including a column, an arm fulcrumed near the upper end of said column, a toy member at the outer end of said arm, means for rotating said arm about said column, control means operable independently of said toy member for applying a positive leverage force on said arm to raise said arm about its fulcrum support, and including a force transmitting member having a point of power application spaced from said fulcrum support, and a control member remote from said arm and said column and manually operable from a stationary position with respect to the rotatable arm to stress said force transmitting member, and means operable from said control member for effecting loop-the-loop rotation of said toy member.

SAMUEL I. BERGER.
